UNITED STATES PATENT OFFICE.

MARY G. PORTER, OF CHARLESTOWN, MASSACHUSETTS.

IMPROVEMENT IN LADIES' SAFETY-BELTS.

Specification forming part of Letters Patent No. 99,347, dated February 1, 1870.

To all whom it may concern:

Be it known that I, MARY G. PORTER, of Charlestown, Middlesex county, in the State of Massachusetts, have invented a new and Improved Lady's Safety-Belt; and I do hereby declare that the following is a full and exact description thereof, reference being had to the accompanying drawing, with letters of reference marked thereon.

The nature of my invention is that of a device for supporting and retaining in its proper position the cloth or bandage used by women at monthly period; and it consists in fastening to a belt two flaps by means of elastic straps. These flaps support the napkin, which is pinned thereto.

In the drawing there is but a single figure, which shows all the parts of my invention, and in the drawing A A is a strap of cloth, leather, or other suitable substance, made of a convenient width, which strap forms about two-thirds of the entire length of a belt made to pass around the waist this portion being that which rests upon the back.

B is another strap, which forms the remaining one-third of the length of the belt. Each end of this strap fits, respectively, into a buckle, which two buckles, C C, are attached by appropriate loops to the respective ends of the strap A A, and are on the outside when the belt is in use.

D D^x are two flaps or lapels, made preferably of cloth, though I do not confine myself to this substance alone. The figure of these is not important, but the most preferable shape is shown in the drawing, being that of one-half of an-oval, (divided by its shortest diameter,) the rounded portion being the lower part. From the straight upper end of each of the flaps proceed up, respectively, three narrow elastic bands, E E E, preferably of shirred rubber fabric. These bands are firmly at-

tached at their upper ends to the respective front and back straps, A A and B, which form the belt.

The mode of operation with my device is as follows: Placing the strap A A round the waist at the back in such manner as that the back flap, D, comes in the center of the back longitudinally, the front strap, B, is then, by means of the buckles C C, fastened to the back strap in such manner that the front flap, D, comes exactly opposite to the other flap—an arrangement which is greatly facilitated by my having in the two buckles two-adjustable fastenings. The ordinary cloth or bandage used is then placed in its usual position, and the ends of the same are then drawn tight and fastened in any convenient manner (preferably by pins) to the respective front and back flaps.

In wearing the device, the elastic straps give perfect facility of instant adjustment, particularly in the act of sitting down, thus giving great ease in wearing while still holding the bandage, which is supported by my device tight and closely to the body.

I do not confine myself to using three bands. I use any number, from one to more, though the number of three to each flap is best; and I prefer buckles to fasten the belt-straps together; but I sometimes use buttons and button-holes, (several on each end of the front strap,) or strings instead thereof, and I sometimes use more than two buckles.

What I claim herein as of my own invention, and desire to secure by Letters Patent, is—

Attaching the supporting-flaps to the belt by means of elastic straps, all arranged as and for the purpose described.

MARY G. PORTER.
